RESISTANCE ELEMENT FOR RHEOSTATS

Alexander W. Piensler, Chicago, Ill., assignor to
Resistelite Corporation, Chicago, Ill., a corpora-
tion of Illinois

Application May 13, 1935, Serial No. 21,080

4 Claims. (CL 201—68)

This invention relates generally to rheostats or the like and more particularly to such devices embodying improved resistance elements produced by a novel, simple and economical process.

An object of the invention is to provide a resistance element of improved form and novel construction which is especially suited for rheostats and like devices for use in radio apparatus and which permits the rheostats to be constructed in exceedingly compact form and yet provide smooth, uniform and accurate resistance control. Another object resides in the provision of an improved resistance element by a novel process, which element is relatively inexpensive to produce, is durable, wear resisting, unaffected by temperature or humidity variations, and which retains its original resistance characteristics indefinitely.

Another object is to provide a novel process of producing resistance elements whereby substantial uniformity of resistance characteristics within narrow tolerance limits may be obtained under quantity production methods.

Another object is to provide a novel process of producing resistance elements wherein the element is built up of relatively thin sheets of resistance material coated with a thin film of varnish, for example, an uncured phenol condensation product which, when cured, binds the sheets together to form a homogeneous, compact mass having uniform resistance characteristics throughout.

Another object is to provide a novel process of producing resistance elements embodying a compact, homogeneous mass of resistance material wherein a relatively large body or block of material having the desired resistance characteristics is built up in laminated form and the individual elements are formed from this block by simple machining operations.

A further object is to provide an improved rheostat having a minimum number of simple and durable parts, which is exceedingly compact in construction, and which is well adapted for very accurate and uniform control of electrical circuits.

Other objects and advantages of the invention will be apparent from the following description taken in connection with the accompanying drawing in which the various elements entering into a preferred embodiment of the invention are shown in enlarged form.

In the drawing:

Figure 1 is a vertical, longitudinal, sectional view through a rheostat embodying the features of the invention.

Fig. 2 is a perspective view of the resistance element.

Fig. 3 is a perspective view of a block of resistance material built up in accordance with the

process of the invention and illustrating certain of the steps in the manufacture of the resistance element shown in Figs. 1 and 2.

Fig. 4 is a perspective view of a strip of the material entering into the construction of the block shown in Fig. 3 from which the resistance elements are formed.

While the invention is susceptible of various modifications and alternative constructions, I have shown in the drawing and will herein describe in detail a preferred embodiment, but it is to be understood that I do not thereby intend to limit the invention to the specific form disclosed, but intend to cover all modifications and alternative constructions falling within the spirit and scope of the invention as expressed in the appended claims.

To illustrate the invention, I have shown in Fig. 1 of the drawing a rheostat particularly adapted for use in remote control units such as are commonly employed with automobile radio sets wherein compactness of construction is very desirable and smooth and accurate resistance control is essential. As shown in the drawing, the rheostat may be enclosed within and forms an integral part of a metal casing 5 of the control unit, thus requiring a minimum of space and materially simplifying construction.

The rheostat comprises generally a resistance element 6 and means for connecting varying portions of the element in an electrical circuit. In its preferred form as shown in Figs. 1 and 2, the resistance element 6 is of substantially cylindrical form and comprises a series of laminations disposed transversely of the axis of the element. A central aperture 7 adapted to receive a contact 8 in sliding engagement with the edges of the laminae provides a connection to one side of the circuit (conveniently the grounded side). A connection to the other side of the circuit is provided by a spring contact 9 adapted to be held in surface engagement with the base of the element 6.

To support the various elements of the rheostat, the casing 5 is formed with a suitable cavity or bore having an intermediate enlargement which constitutes a receptacle for the resistance unit 6. The enlargement is preferably of slightly greater diameter than the element to provide space for a sleeve 9^a of any suitable insulating material for preventing electrical contact between the sides of the element and bore. The inner end of the element 6 is preferably insulated from the casing 5 by means of an insulating element 10 which may conveniently be formed integrally with the element. The resistance element is thus enclosed within the casing 5 but is insulated therefrom and the outer end is disposed for convenient engagement by the spring contact 9.

To facilitate assembly of the rheostat and to provide for readily connecting the same in circuit, the spring contact 9 may conveniently be incorporated in a removable plug assembly. As shown herein, the contact spring 9 is of generally U-shaped form and is carried in a shallow cup 11 of suitable insulating material. One leg of the spring 9 is bent upwardly so as to project above the rim of the cup 11 and the other leg rests upon the bottom of the cup and is soldered or otherwise suitably secured to the end of a conductor 12 projecting through the bottom of the cup. To hold the spring firmly in place, a washer 13 engaging the outer surface of the cup and soldered to the conductor 12 may be provided.

To hold the cup 11 and spring contact 9 in position in the rheostat, the plug assembly includes a sleeve member 14 threading into the bore in the casing 5 and bearing against the bottom of the cup 11. Conductor 12 which leads to the radio set or circuit to be controlled extends rearwardly through the sleeve 14. To protect the conductor from such contact with the sleeve as would tend to wear off and weaken the insulation, a bushing 15 is provided at the outer end of the sleeve. The bushing 15 may be formed of any suitable material such as soft rubber which further prevents the conductor from being bent sharply at the point of leaving the sleeve and thus adds to the life of the equipment.

Sliding contact by which the resistance of the element 6 is variably included in the electrical circuit is provided by the contact member 8. As shown herein, the contact member 8 is in the form of a split metal pin formed integrally with or suitably secured to a screw 16 and adapted to project into the aperture in the element 6. The arms of the pin flare outwardly so as to yieldably engage with the cylindrical surface of the aperture, the resiliency of the metal holding them in firm electrical engagement therewith. The ends of the legs may be rounded to minimize wear on the element.

The screw 16 which carries the contact member 8 is adapted to thread into the bore in the casing 5 and is thus movable by minute increments of adjustment toward and from the stationary element 6. To facilitate the rotation of the screw 16, a suitably formed knob 17 is rigidly secured to the outer end of the screw 16. The movement of the screw regulates the position of the contact members 8 with respect to the element 6 and thereby controls the resistance of the circuit. Movement of the contact member 8 toward the rear of the element increases the gap between the member and the contact spring 9, thus providing a longer conductive path through the element with a resultant increase in resistance while a reverse movement reduces the circuit resistance. The threads of the screw 16 may, of course, be formed with any desired lead so as to provide the requisite sensitivity of adjustment.

The screw 16 provides electrical connection with the casing 5 and thus with the other side of the circuit. Ordinarily, the casing will be mounted upon a metal part of the car which, in the usual practice, is "grounded" to one side of the battery. This connection is illustrated diagrammatically by a conductor 18 shown as attached to the casing 5. It will be appreciated that this conductor may be connected at any point on the frame with which the casing is in contact.

The compact construction, uniform and accurate resistance control as well as the sensitivity and reliability of the rheostat is made possible

not only by the simple construction above described, but by the improved resistance element 6 which is a product of the novel process of manufacture contemplated by the invention. It will be apparent that the element 6 may be made in any desired shape but that the cylindrical form is to be preferred as it lends itself most readily to efficient manufacture both with respect to the element itself and to the associated parts which, with the element, constitute the completed device.

To provide the most efficient control device for a particular electrical circuit, the resistance characteristics of the resistance element employed must be determined to meet the requirements of that circuit. Thus in one instance, an element having substantially uniform resistance throughout its entire length may be required, while in another instance, a "taper" or non-uniform change in resistance per unit of length of the element may be desirable. Moreover, the overall resistance required in a circuit as well as the rate at which variation is desired must be taken into consideration in forming the resistance elements. In the case of resistance elements formed of a mass of finely divided or comminuted material, it is exceedingly difficult to meet these requirements with any degree of accuracy. Thus, there is not only the problem of providing a resistance element which will meet particular circuit requirements but also of producing the elements with a reasonable degree of uniformity. In quantity production, particularly, uniformity within quite narrow tolerance limits is essential but difficult to obtain.

By the present process it is a relatively simple matter to produce resistance elements having any desired resistance characteristics. Moreover, it is possible to produce resistance elements in large quantities which elements are of substantially uniform character, variations being held within materially closer limits than has heretofore been practical. Briefly, the present process contemplates the production of resistance elements in laminated form, the resistance material being first incorporated in relatively thin sheets which sheets are then united by means of a suitable binder to form a homogeneous block of resistance material having the desired resistance characteristics. The individual elements are then produced from this block by simple machining operations.

Referring more particularly to the process of forming the block of resistance material from which the elements are produced, the laminae or sheets from which the block is formed preferably comprise sheets of absorbent material carrying in intimate association finely divided particles of resistance material. The sheets may be formed by immersing a sheet of suitable absorbent material in a bath containing finely divided particles of a selected resistance material under suitably controlled temperature and other conditions.

Many types of absorbent material may be used, a good grade of absorbent paper being particularly suitable. For the sake of uniformity, the paper should be of even texture throughout so that the finished product will be substantially free of variations. Likewise, any suitable resistance material may be used, a preferred material being graphite. This material, in finely divided form, is held in suspension preferably as a colloid, in a suitable fluid such as water, the concentration depending upon the amount of material which the sheet is to take up. Upon the sheet being immersed in the bath, the suspended material is uni-

formly distributed through its fibers and is held therein when the sheet is removed. Thus, a sheet may be produced with any desired resistance characteristics and may readily be duplicated within close limits.

After treatment as above described, the sheet is carefully dried and then coated with a thin varnish, preferably an uncured phenol condensation product. The varnish is applied in sufficient amount to bind a graphite coated sheet to another sheet without, however, insulating them from one another. A partially coated sheet is shown in Fig. 4 by way of illustration. In that figure, the reference character 19 designates a coated portion 10 of the sheet having the finely divided particles of resistance material uniformly distributed throughout while the thin coat of varnish thereon is indicated at 20.

The next step in the process is to build up the 20 block of resistance material from the coated sheets above described. Accordingly, a number of sheets carrying the proper amount of resistance material to give the desired results are placed one on top of another to form a stack of the required dimensions. To produce resistance elements having 25 uniform resistance characteristics throughout, sheets carrying substantially identical quantities of resistance material will be employed. To produce elements with a "taper", sheets having varying 30 quantities of the resistance material will be used and these will be arranged in the proper sequence necessary to give the desired resistance characteristics to a completed unit.

Upon the top of the stack of coated sheets a 35 final untreated sheet 21 of fiber may be placed which is coated with the varnish but which carries no resistance material. This sheet is employed where it is desirable to insulate one end of the resistance elements from their supporting structure as in the instance hereinbefore described. The entire stack of sheets is then cured under heat 40 and pressure, the varnish binding the sheets together into a substantially solid mass or block 22 through which the finely divided particles of resistance material are uniformly and conductively dispersed.

After curing, the block 22 may be formed into 50 resistance elements in any convenient manner. As herein shown, apertures 7 are first formed in the block 22 as by drilling, the apertures being spaced to provide sufficient material from which to form the elements 6. The block is then cut into substantially square sections 23, each section having one of the apertures 7 included therein. The square sections 23 may, of course, be used in 55 this form, if desired, or they may be turned to the cylindrical form shown in Fig. 2. In producing the cylindrical elements it has been found convenient to mount the square sections upon an arbor held in a lathe and to turn them down in a conventional manner. The elements are thus produced with an accurately centered aperture 7 so that the laminae comprise substantially annular sheets of resistance material. The elements 60 may readily be formed to exact dimensions which, with the carefully controlled process of forming the material, makes it possible to obtain an unusual degree of uniformity in elements produced under quantity production methods.

70 In view of the foregoing, it will be apparent that

the resistance element 6 formed in the above manner presents a smooth, hard, wear resisting surface for engagement by the sliding contact 8. Thus the element is durable and its resistance characteristics remain unchanged in use. Moreover, these characteristics are unaffected by temperature or humidity variations. The element does not produce electrical noise in use and is therefore especially suitable for radio use. Its homogeneous character permits very accurate 10 and uniform resistance control. Further, rheostats employing the improved elements may be constructed in extremely compact form without sacrificing accuracy or other desirable characteristics.

It will also be apparent that I have devised a novel process of producing resistance elements by which process the elements can be readily made to any desired standard. Further, the resistance elements produced by this process are of substantially uniform character which greatly facilitates their manufacture in commercial quantities.

I claim as my invention:

1. An elongated resistance element having a longitudinally extending contact surface, said 23 element comprising a plurality of sheets of absorbent material carrying uniformly dispersed finely divided resistance material, said sheets being disposed transversely with the edges thereof providing said contact surface and bonded together to produce a substantially solid mass in which the sheet edges form said contact surface.

2. An elongated resistance element having a longitudinally extending contact surface, said element comprising a plurality of sheets of absorbent 35 material carrying uniformly dispersed finely divided resistance material, said sheets being stacked in face-to-face relation and disposed so that the edges of the sheets present a contact surface, a sheet of insulating material disposed at 40 one end of the stack of absorbent sheets to form an insulating terminal for one end of the element, and means bonding said absorbent sheets and said insulating sheet together to form a substantially solid mass.

3. A resistance element comprising a plurality of sheets of absorbent material impregnated with finely divided particles of resistance material, said sheets being substantially annular in form and disposed in surface-to-surface contact to 50 define an elongated tubular element with the edges of the sheets defining a contact surface extending longitudinally of the element, and means permanently binding said sheets together to form a substantially solid mass.

4. A resistance element for a variable resistor device comprising the combination of a stack of sheets arranged in laminated form, said sheets carrying predetermined quantities of resistance material selected to afford desired resistance 60 characteristics measured across the stack, and means for permanently combining said sheets to form an integral unit capable of being handled as such during its assembly in and removal from the resistor device, said unit having a contact 65 area extending across the stack of sheets with edge portions of the sheets providing for current conductivity to the sheets as segments of the element.

ALEXANDER W. PLENSLER. 70
